DESIGN FOR A DRESS

Louis Katz, New York, N. Y.

Application December 11, 1939, Serial No. 88,810

Term of patent 3½ years

To all whom it may concern:

Be it known that I, Louis Katz, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides

in the combination on the specific net dress disclosed of the specific embroidered blouse portion having ruffle trimmed sleeves and a matching trimmed neck opening with bows at each side thereof in association with the row of shirring extending down the center front of the blouse portion, as shown.

I claim:

The ornamental design for a dress, substantially as shown and described.

LOUIS KATZ.
